DISTRIBUTING STICK FOR TYPE

Filed Sept. 4, 1924

FIG. 1

FIG. 2

FIG. 3.

FIG. 4.

INVENTOR
WILLIAM H. STOREY
BY Richards, Liver
ATTORNEYS

UNITED STATES PATENT OFFICE.

WILLIAM HENRY STOREY, OF LEICESTER, ENGLAND.

DISTRIBUTING STICK FOR TYPE.

Application filed September 4, 1924. Serial No. 735,747.

To all whom it may concern:

Be it known that I, WILLIAM HENRY STOREY, a British subject, residing at 30 Mere Road, Leicester, England, Great Britain, have invented new and useful Improvements in Distributing Sticks for Type, of which the following is a specification.

The present invention relates to improvements in distributing sticks for types, more particularly for use with type used in rototype or like printing machines.

The sticks hitherto used for this purpose have been constructed with an open end fashioned with prongs, the other end being closed. In action the prongs have been inserted into the channels of the forme and the types have been slidden into the stick. To distribute the types into the composing fount an adaptor has been used, the said adaptor being constructed as a loose part which has been fitted on to the open end of the stick.

The adaptor serves a double purpose in that as well as allowing one type at a time to be extracted it also acts as the sole means for retaining the types in the distributing stick. It is obvious therefore, that should the operator inadvertently tip the fork angularly or vertically with the pronged end pointing downwards, before or whilst fitting the adaptor the type will be spilt, thus causing great wastage of time in picking up the type and re-inserting it in the fount or fork. Moreover, the type may be inserted wrongly in the fount or fork, with the result that later on, further time is wasted and much delay caused when the proof is taken and the characters are found to be upside down.

Furthermore, the fact that hitherto adaptors have been constructed as separate devices has the disadvantage that these may get mislaid or damaged by being dropped on the floor and trodden on. They also take considerable time to fit in position and as they are awkward to fit it is during this process that the type is liable to be spilt.

Now the object of the present invention is to improve upon the construction of distributing sticks and the adaptor for use therewith in such a manner that these difficulties are overcome.

The invention consists in a distributing

stick provided with a closed end and a pronged end, an adaptor pivoted at a point 55 near the pronged end so that it can be moved into and out of operative position and a type retaining device which acts when the adaptor is out of operative position to prevent spilling of type if the stick is tilted 60 with the prongs pointing downwardly.

The characteristics of this distributing stick for type as well as its mode of operation will now be fully described, reference being had to the accompanying drawings 65 whereon:—

Fig. 1 shows in elevation a distributing stick to which the invention has been applied.

Fig. 2 is an enlarged plan view of the 70 distributing end of the stick.

Fig. 3 is a sectional elevation of Fig. 2 showing the adaptor in its inoperative position, in which position the type retaining device can function to prevent the escape of 75 types from the open end of the stick, should the stick be tilted.

Fig. 4 is a similar view to Fig. 3 but with the adaptor turned to the position for distributing type into the composing fount. 80

As will be seen from the drawings the invention is for convenience applied to a distributing stick of tubular construction, although it is to be understood that the formation or appearance of the stick may be 85 varied.

The stick 1 is provided with the usual central slot 2 one end being fitted with a stop 3 while the other end of the stick is fashioned with prongs 4 shaped to suit the channels in the forme. The adaptor 5 is provided with an extension piece 5^a through which passes a pivot 6 housed in the stick 1. The extension piece is further provided with a pin 7 or projection upon which presses a 95 spring 8 secured to the stick in any convenient manner as by a rivet 9, screw or other means. The spring 8 acts upon the pin 7 in the adaptor in such a manner that when the pin is at one side of the pivot 6 the spring 8 is pressing the adaptor 5 securely into operative position as is clearly seen by Fig. 4, and when the adaptor is turned into the position shown in Fig. 3. 100 the pin 7 is acted upon by the spring 8 and the adaptor is retained securely in its in-

operative position. The extension piece 5^a of the adaptor is cut away to form a tooth or teeth 10 which contacts or contact with a tooth or teeth 11 formed on a detent 12 which is pivoted at 13 in the stick. A spring 14 has its intermediate portion coiled about the pivot 13 with one end engaging the pivot 6 and its other end contacting the under surface of the detent 12 so as to normally exert a yielding pressure on said detent to force the free end thereof in a downward direction toward the position shown in Figure 3. When the adaptor 5 is moved to its operative position shown in Figure 4 the tooth or teeth 10 will engage a tooth or teeth 11 of the detent and pressure upon the adaptor will force said detent to the position shown in Figure 4 against the tension of the spring 14. It should be noted that when the adaptor is swung into its inoperative position the tooth or teeth 10 leaves or leave the tooth or teeth 11, when the movement of the detent 12 is arrested by its angled leg 12^b striking the spring 8.

The type retaining device is similar in principle to the means described and claimed in my former application for a patent Ser. No. 735,746, filed September 4, 1924 relating to a type composing stick, wherein a ball is adapted to move into the path of the type by means of an inclined race, a stop being provided at the bottom of the race the said stop forming a cup or nest to keep the ball clear of the bases of the types when the stick is held in an upright position. In the said application for a patent the inclined plane was formed from the stick as an element secured thereto in a fixed position.

According to the present invention the inclined race is formed in one with the detent 12 so that the movement of the ball 15 to act as type retaining means only comes into action when the adaptor 5 is in its inoperative position (Fig. 3.) and consequently the type 16 cannot drop out of the slot or channel 2 of the stick 1 as formerly has been the case. The ball race is formed by an extension piece 12^a of the detent 12 which may be provided with a downwardly projecting piece 12^b so that when the adaptor 5 is in its operative position the ball is retained in a pocket between the part 12^b of the detent and the fixed stop 17.

It is to be understood that the position of the ball 15 shown in Fig. 3. is achieved by tilting the stick so that the free or distributing end of the stick is lowered.

In operation, the adaptor 5 is first swung into its inoperative position (Fig. 3.) and the prongs 4 on the open end of the stick 1 are inserted in the channels of the forme and the types are slid from the forme into the slot or channel 2 and the stick during this operation being in a horizontal po-

sition the ball 15 is at the bottom of the inclined race, in its nest or pocket, thus allowing free passage of the type into the stick.

Should the stick be inadvertently tilted with the prongs 4 pointing downwardly the ball 15 will ride up the race 12^a into the path of the type 16 and prevent their escape.

To distribute the type into the fount, the adaptor 5 is swung round into operative position, Fig. 4. and in this position the race 12^a formed by the detent 12 is raised through the tooth or teeth 10 of the extension 5^a of the adaptor 5 striking on the tooth or teeth 11 of the detent 12 so the ball 15 is retained in the pocket before mentioned and therefore cannot move into the path of the type, with the result that the type 16 can pass to the adaptor 5 and be extracted therefrom one at a time in the usual manner.

The type distributing stick is provided with the usual thumb and finger piece 18.

Having thus described my invention what I desire to secure by Letters Patent of the United States is as follows:—

1. A distributing stick for type provided with a closed end and a pronged end, characterized in that an adaptor is so pivoted at a point near the pronged end that it can be moved into and out of operative position forming a connected part of the distributing stick with no loose parts to be lost or damaged.

2. A distributing stick for type as claimed in claim 1 characterized in that the movement of the adaptor to its inoperative position operates mechanism which permits a type retaining device to function so that types cannot inadvertently be spilled.

3. A distributing stick for type as claimed in claim 1 characterized in that the adaptor is provided with an extension piece through which passes a pivot housed in the stick, a pin or projection on the extension piece and a spring secured to the stick the spring acting to retain the adaptor in its operative or inoperative position through pressure upon the pin or projection.

4. A distributing stick for type as claimed in claim 1 characterized in that a detent is pivoted to the stick, the said detent being formed with projections to be engaged by similar projections formed on the extension piece of the adaptor and held normally in contact therewith by means of a spring.

5. A distributing stick for type as claimed in claim 1 characterized in that the detent is pivoted to the stick and formed with an extension constituting a ball race, said detent being further formed with a projection to be engaged by a similar projection formed on the extension piece of the adaptor and held normally in contact therewith by means of a spring.

6. A distributing stick for type comprising in combination an adaptor pivotally connected to the stick, a projection formed on an extension of the adaptor, a detent pivoted to the stick provided with a projection, at one extremity and a ball race at its other extremity, a ball situated in the stick

between the race and a stop, the said ball acting as means to retain the type in the way and manner specified.

10

In testimony whereof I have signed my name to this specification.

WILLIAM H. STOREY.
